(57) CLAIM

I claim the ornamental design for a wax warmer, as shown and described.

DESCRIPTION

FIG. 1 is a Perspective view of a wax warmer showing my new design;

FIG. 2 is a Front view of the wax warmer as shown in FIG. 1;

FIG. 3 is a Back view of the wax warmer as shown in FIG. 1;

FIG. 4 is a Right-side view of the wax warmer as shown in FIG. 1;

FIG. 5 is a Left-side view of the wax warmer as shown in FIG. 1;

FIG. 6 is a Top view of the wax warmer as shown in FIG. 1; and,

FIG. 7 is a Bottom view of the wax warmer as shown in FIG. 1.

The broken lines showing in the drawings are included for the purpose of illustrating environmental structure and form no part of the claimed design.
